UNITED STATES PATENT OFFICE.

LEON LE PONTOIS, OF PITTSBURG, PENNSYLVANIA, ASSIGNOR OF FIVE EIGHTHS TO JOHN V. PATTON AND WILLIAM S. HAUGH, OF SAME PLACE.

FLUID-PRESSURE GENERATOR.

SPECIFICATION forming part of Letters Patent No. 617,753, dated January 17, 1899.

Application filed December 5, 1898. Renewed January 24, 1898. Serial No. 667,815. (No model.)

To all whom it may concern:

Be it known that I, LEON LE PONTOIS, a citizen of the Republic of France, residing in Pittsburg, in the county of Allegheny and State of Pennsylvania, have invented a new and useful Improvement in Fluid-Pressure Generators, of which the following is a specification.

My invention relates to apparatus for producing fluid-pressure by the explosion of a mixture of hydrocarbon vapor and air or other explosive gaseous mixture; and it has for its object to provide an apparatus of this character which shall be extremely simple and durable in construction and efficient in operation. In order to attain the desired results, I employ a plurality of pressure-generating chambers, preferably two, of constant capacity, which act upon each other in such manner that an explosion in either of them exhausts from the other the inert residual products of the preceding explosion therein and effects the introduction into it of a body of fresh air and a sufficient quantity of oil-vapor or gas to form the proper mixture for a new explosion, which will then occur and effect the same results in connection with the adjacent chamber. It is apparent that the efficiency of apparatus of this general character as usually constructed is comparatively low on account of the fact that the piston velocity is so small that the hot air cannot expand freely and do mechanical work by following an adiabatic curve. The piston velocity is limited on account of mechanical considerations and the necessary cooling of the cylinder absorbs much of the heat-energy.

By dispensing with all moving parts in the pressure-generating chambers and causing the explosive mixture to act directly in an air-injector, so as to set a large volume of air in motion, which transmits the energy received to a movable agent, the efficiency of the machine is greatly increased. Owing to the large number of explosions which can take place in each chamber per minute the heat losses due to convection or radiation may also be materially smaller than in any ordinary gas-engine.

In the accompanying drawings I have illustrated apparatus constructed in accordance with my invention, in which—

Figure 1 is a vertical section taken on line *xx* of Fig. 2, and Fig. 2 is a horizontal section taken on line *yy* of Fig. 1. Fig. 3 is a detail sectional view, on an enlarged scale, of the valve mechanism for introducing oil into the pressure-generating chambers. Fig. 4 is a view, partially in side elevation and partially in section, illustrating the adaptation of my invention to boat propulsion. Fig. 5 is a similar view illustrating my invention as utilized for the production of rotary motion for general power purposes.

Reference being now had to the details of the invention as shown in the drawings, 1 is the main body or casing of the apparatus, divided into two compartments or chambers 2, located side by side and each having an exhaust port or outlet 3. These exhaust-ports are communicating and, as shown in the drawings, combine to form a single outlet port or nozzle 4. The partition 5, separating the two chambers 2, is preferably made hollow, and a burner 6 is located in the chamber 7 thus formed and serves to raise the temperature of the edge of the partition to a red heat, so as to ignite the explosive mixture. The heat-producing agent may, however, be applied to the outer sides of the chambers near the exhaust-ports, if desired.

The bottom of each chamber is provided with a thin steel plate 8, which is heated by a burner 9 in order to raise the temperature of the contents of the chamber to such a degree that the oil injected into it will be rapidly vaporized. The form and relative arrangement of the parts thus far described may obviously be materially varied from what is shown without affecting the mode of operation or impairing the efficiency of the apparatus—for example, the chambers or their exhaust-ports may be placed concentrically, as in a steam-injector—but I regard the form and arrangement illustrated as particularly simple and such as will give good results in practice.

I provide each chamber with one or more openings 10 for the admission of air, two being shown in the drawings. Each of these openings is provided with an inwardly-opening check-valve 11, normally held to its seat by a coiled spring 12. I have shown the valved openings as located at the top of each

chamber; but they may be otherwise located, if desired.

Projecting from one side of each chamber 2, preferably the top, is a cylinder 13, the bottom or inner end of which is in open communication with said chamber. Its top or outer end is provided with an opening 14, which communicates with a pipe 15. The opening 14 is provided with an inwardly-opening valve 16, normally held to its seat by a coiled spring 17. Closely fitting the interior of the cylinder 13 is a hollow piston 18, normally retained in its innermost position at the bottom of the cylinder by a coiled spring 19. Inside the hollow piston 18 is a small piston 20, also normally held depressed by a coiled spring 21 interposed between it and the upper end of the piston 18.

Projecting into the chamber 2 from the lower end of the piston 18 is a perforated tube 22, which communicates with the interior of the piston, when the latter is in its lowest position, by means of passages 23 and 24 in the bottom and sides of the piston and passages 25 in the side walls of the cylinder.

Extending upward through the side and top walls of the piston 18 from the passages 24 are passages 26, which communicate with the upper end of the cylinder by means of an opening 27, provided with an inwardly-opening check-valve 28, normally held to its seat by a coiled spring 29.

30 is a rod by means of which the piston 18 may be actuated in order to provide the pressure-generating chamber with the hydrocarbon vapor necessary for the initial explosion. The branch pipes 15 extend to a single pipe 31, which leads from an oil-tank 32 and is provided with a hand-valve 33.

40 The operation of the apparatus is as follows: Assuming that the air contained inside the chambers has been heated to such a temperature that the oil injected into it will be readily vaporized and assuming also that the edge 45 of the partition 5 is red-hot, so as to ignite an explosive mixture, one of the pistons 18 is raised by means of its rod 30 and the spring 19 thus compressed. Communication between passages 24 and 25 is thus cut off, and 50 at the same time valve 28 is forced from its seat and oil is forced from the upper portion of the cylinder through passages 25 and 24 into the chamber in piston 18 below piston 20, thus compressing spring 21. As the rod 55 is released the piston 18 is depressed by the spring 19, and the action of spring 21 upon piston 20 will force a portion of the oil beneath it out through passages 24, 25, and 23 into the tube 22, from which it will be sprayed 60 into the chamber and instantly vaporized, the supply being continued until the proper mixture is produced. Part of the mixture comes into contact with the red-hot edge of the partition, is ignited, and causes the ignition of 65 the whole of the mixture contained in the chamber.

It will be observed that the explosion of

that part of the mixture located near the exhaust-port exerts a certain pressure upon the non-ignited part, and thus serves to effect a 70 more intimate mixture of the air and oil-vapor. The explosive mixture is ignited mainly by convection, and consequently cannot leave the chamber without exploding. As the explosion takes place it effects a violent expulsion of air and gas through the exhaust-port 75 3 and the nozzle 4, thus creating a partial vacuum in the adjacent chamber. Each explosion also exhausts the chamber in which it takes place to some extent. If an explosion 80 has previously taken place in the adjacent chamber and if it is partially filled by the products of the former explosion, these products are drawn out, and in any event a partial vacuum is thus produced, by reason 85 of which the check-valves are opened and fresh air admitted and the oil-feeding piston-valve worked up and down, an explosion takes place, the products of the first explosion are drawn from the adjacent chamber, 90 which is in turn filled with fresh air and subsequently with oil-vapor, after which the action becomes automatic, the two chambers controlling each other. It is thus apparent that these chambers will be alternately charged 95 and exhausted and that the explosions will take place very rapidly. The time elapsing between consecutive explosions, and consequently the mean pressure exerted thereby, may be regulated by means of the valve 33, 100 since the time occupied by the movement of the piston 18 depends upon the rapidity with which the upper portion of cylinder 13 is filled with oil.

After several explosions have taken place 105 the chambers become heated to such a degree that the external burners beneath the plates 8 may be dispensed with, the burner heating the edge of the partition being retained in order to keep it at red heat, so as to 110 ignite the mixture when the right proportions of vapor and air are reached.

It has been assumed in the foregoing description that the inertia of the oil-feeding valves and the spring-pressure which returns 115 them to their normal positions are equal, and therefore that the time lag between two consecutive explosions is constant for a given opening of the speed-regulating valve. It will be readily understood that if such conditions do not substantially obtain in practice 120 the two valves may be respectively connected to the opposite ends of a pivoted beam or otherwise controlled so as to act alternately.

Referring now to Fig. 4, 34 is a section of a 125 boat provided with a longitudinal tube 35, open at both ends and extending along its keel. 36 is a curved pipe or passage leading into the side of the tube 35 and provided with a reversing-valve 37, operated by a screw 38, a pinion 39, gear-wheel 40, and hand-wheel 41, or by any other suitable means. Mounted upon supporting and guiding rods 42 so as to be adjusted longitudinally thereon are two

tapered pipes or nozzles 43 and 44. These pipes or nozzles are in alinement with the nozzle 4 and the upper end of the pipe or passage 36. Any desired number of these devices may be employed in order to provide for injecting a large volume of air at a low velocity into the passage 36 to set the column of water in the tube 35 in motion by suction and impact and thus effect the propulsion of the boat.

The arrangement of apparatus shown in Fig. 5 is similar to that shown in Fig. 4 except that the column of air set in motion by the engine acts against the vanes 45 of an air-motor 46, the shaft 47 of which is provided with a belt-pulley 48. The object of this arrangement is to avoid the condensation which would take place if the product of the explosion were caused to act directly upon the turbine. It is true that there is a certain degree of condensation caused by setting the cool air in motion; but this condensing effect is relatively small, and as the air set in motion has a large volume and a small velocity the velocity of the turbine may be much less than that of the ordinary steam-turbine, and the conditions of maximum efficiency are therefore more nearly attainable.

This fluid-pressure generator, in connection with the compound air-injector, may also be utilized for air-blasting machines and for the ventilation of mines.

The adaptability of my invention to other uses will be obvious without further illustration or description, the examples given being merely illustrative and not in any sense limiting.

What I claim is—

1. A fluid-pressure generator comprising two pressure-generating chambers of constant capacity having adjacent communicating exhaust-ports and means for effecting explosions in said chambers alternately, whereby they alternately exhaust each other.
2. A fluid-pressure generator provided with a plurality of pressure-generating chambers having adjacent exhaust-ports permanently in open communication therewith, in combination with means for producing dissimultaneous explosions in said chambers, whereby each explosion effects the exhaustion of an adjacent chamber.
3. A fluid-pressure generator having two pressure-generating chambers of constant capacity provided with communicating exhaust-ports, in combination with means for introducing an explosive mixture into said chambers and means for effecting the explosions alternately, whereby the chambers are alternately exhausted by suction.
4. A fluid-pressure generator comprising two pressure-generating chambers of constant capacity provided with communicating exhaust-ports, in combination with igniting means and alternately-actuated air and gas inlet valves.
5. In a fluid-pressure generator, the combination with two pressure-generating chambers of constant capacity provided with valves for admitting air, of gas-supplying mechanism comprising cylinders communicating with said chambers and provided with compound pistons.
6. Gas-supplying means for a fluid-pressure generator comprising a cylinder open at one end and provided with an inlet-valve at the other, in combination with a hollow piston normally spring-pressed toward the open end of the cylinder and provided with a valved opening and a second spring-actuated piston located in said hollow piston.
7. The combination with a cylinder having an inlet-valve at one end, of a hollow piston in said cylinder provided with a passage communicating with the cylinder at one end by means of a valved opening and permanently in open communication with its interior and with a passage leading to the exterior of the cylinder when the piston is at one extremity of its movement, and a second piston located in and movable independently of said first-named piston.
8. A fluid-pressure generator comprising two pressure-generating chambers of constant capacity having communicating exhaust-ports, means for supplying an explosive mixture to said chambers alternately and means for alternately exploding said mixture, in combination with one or more nozzles into and through which said explosion-chambers exhaust.
9. A fluid-pressure generator having two pressure-generating chambers of constant capacity provided with adjacent, permanently open exhaust-ports and means for effecting alternating explosions in said chambers.
10. The combination with two pressure-generating chambers of constant capacity having adjacent communicating exhaust-ports and a single outlet-nozzle, of means for effecting alternating explosions in said chambers, and one or more tapering injector pipes or nozzles in line with said outlet-nozzle to increase the volume and diminish the velocity of the fluid under pressure.
11. The combination with a plurality of pressure-generating chambers of constant capacity, having adjacent communicating exhaust-ports and a single outlet-nozzle, of means for effecting explosions alternately in said chambers, a wind-wheel or turbine, and one or more injector pipes or nozzles intermediate said outlet-nozzle and said wind-wheel or turbine.

In testimony whereof I have hereunto subscribed my name this 30th day of November, 1895.

LEON LE PONTOIS.
